UNITED STATES PATENT OFFICE.

JULIUS RIEDEL AND ALBERT PFLÜGER, OF BERLIN, GERMANY, ASSIGNEES
TO CARL BRÄMER, OF SAME PLACE.

MATCH-BOX.

SPECIFICATION forming part of Letters Patent No. 233,803, dated October 26, 1880.

Application filed July 30, 1880. (No model.) Patented in Germany December 12, 1879.

To all whom it may concern:

Be it known that we, JULIUS RIEDEL and ALBERT PFLÜGER, subjects of the King of Prussia, residing at the city of Berlin, in the 5 German Empire, have invented certain new and useful Improvements in Match-Boxes; and we do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 Our invention relates to improvements in match boxes, stands, or safes for use upon tables or counters, or on walls, or as pocket match-safes; and it consists in certain details of construction and arrangement, all as hereinafter fully described, and shown in the accompanying drawings, in which—

Figure 1 represents, in elevation, the device employed as a match-stand. Figs. 2, 3, and 4 represent, respectively, a plan view, a side, and 25 end elevation of the match-receptacle proper, the outer casing and stand being removed. Fig. 5 is an isometrical view of an ordinary paper match-box, the bottom thereof being removed. Figs. 6 and 7 are like views, showing 30 the device arranged for use as a pocket match-safe or a wall match-safe. Fig. 8 is a like view of the devices arranged more particularly for use as a pocket-safe, and Figs. 9 and 10 are detail views of the same.

35 In the accompanying drawings like letters of reference are employed to indicate like parts wherever such may occur.

A represents a casing of any desired form, preferably of rectangular or oblong shape, and 40 made of any suitable material, such as wood, metal, pasteboard, papier-maché, &c. It has has a recess, a , below its bottom, and is attached to or set on a suitable stand, a' , provided with an enlarged base, a^2 , which may 45 serve as a receptacle for matches after having been used.

B is the match-receptacle proper, provided with a series of compartments, b' , extending from the bottom to the top of the receptacle.

These compartments, which are preferably 50 made of undulating sheet metal or other suitable material, pressed, stamped, molded, or otherwise made into the undulating shape shown, are hinged together, as shown at C, Figs. 3 and 4, so that the device may be opened somewhat like a book for the insertion of the matches. The upper end of each compartment is provided on its interior surface with some gritty substance, such as fine sand, emery, or any one of the substances usually employed 60 for forming the friction-surfaces on the ordinary match-boxes, for the purpose of igniting the matches as they are withdrawn from their respective compartments. This hinged receptacle or receptacles, when filled with matches, 65 are inserted into the casing A, which has on its opposite sides springs b , for the purpose of compressing or holding the compartments b' firmly together, as shown by dotted lines, Fig. 4.

In Fig. 5 we have shown the ordinary form of match-box or match-wrapper, usually made of paper or thin pasteboard, and provided with a lid or cap, or made to slide in an inclosing-case. The compartments b' for the matches are 75 here made of stiff paper of the undulating shape shown, the strips being provided at the upper edges with roughened or friction surfaces to ignite the matches when withdrawn; and, if desired, these paper receptacles B may be employed in conjunction with the inclosing-case A, being less costly than the metallic receptacles above referred to.

In Figs. 6 and 7 we have shown the receptacle B arranged in book form and provided 85 with two intermediate leaves, L, hinged with the match-receptacles b' at C, said leaves being provided at their upper edges with roughened or friction surfaces D, so that when the device is folded the leaves L will form the inclosure for the inner side of said receptacles b' , and when a match, G, is withdrawn the igniting material at one end thereof will come in contact with one or the other of the friction-surfaces D and be ignited, and, if desired, a 90 lid or cover, b^2 , may be hinged to one of the outer leaves, as shown in dotted lines at h , Fig. 6, to cover the top of the match-safe.

Instead of extending the compartments the entire length of the match-receptacles, a series of sockets may be formed at the lower end thereof by means of a narrow strip of undulating or fluted material, to isolate that part of the match to which the igniting material is applied, and provided with guards b^3 at the upper edges of each receptacle, to prevent the matches from slipping out laterally, as shown 10 in Fig. 7, and any number of such receptacles may be employed.

The arrangement of match-safe shown in Figs. 6 and 7 may be employed as wall-pockets by providing suitable means to suspend 15 them from a nail or other like support, and suitable hasps to hold the parts together when so suspended; or a lid may be hinged thereto, as shown in Fig. 6, and the safe may be employed as a pocket match-safe.

20 In Figs. 8, 9, and 10 we have shown the devices arranged more particularly for use as pocket match-safes. The casing A, open at top and bottom, is here provided with a slot, S, and either one of the receptacles B, (shown 25 in Figs. 6 and 7,) provided on one side with a stud or pin, P, and at the other with a lid, b^2 , hinged at h , is inserted into the open casing, the act of insertion automatically closing the lid over the outer casing, A, and when the device 30 is grasped as shown in Fig. 8 and the receptacle B shoved upward by the application of the thumb to the pin P, projecting through the slot S, the lid will automatically fly open and the match ends will project above the case 35 sufficiently to be taken hold of and withdrawn, and by so doing they will be automatically ignited, as will be readily seen.

Of course it will be understood that the matches are placed in the compartments b^1 40 with their heads down, so that the match has to be almost wholly withdrawn before said heads come in contact with the friction-surface.

The paper case (shown in Fig. 5) may be left 45 open at top and bottom, and inserted or placed into open-sided holder B', Fig. 10, and the two placed in the casing A, Figs. 8 and 9, and used as a pocket match-safe, said paper receptacle B, Fig. 5, being thrown away as use- 50 less when the contained matches are used up, when a fresh one may be inserted in its place.

When the receptacles, Figs. 6 and 7, are used in conjunction with the inclosing-ease A, open at top and bottom, as shown, Figs. 8 55 and 9, the lid b^2 will form the top of the safe, and the hinged lower or bottom ends of said receptacle B will form the bottom of the outer casing, A, the same taking place when the paper receptacle, Fig. 5, is employed only.

60 Here the holder B' will form the closure for both the bottom of the paper receptacle and that of the outer casing, while the lid of said holder will form a like closure for the top of the receptacle and the outer casing, A, as will 65 be readily understood by an inspection of the drawings.

In order to insure the ignition of the matches when the compartments are extended from top to bottom of the receptacle, these compartments may be made slightly tapering from 70 bottom upward to insure frictional contact of the match-head with the roughened surface at the upper end of the compartment, though I have found in practice that the application of sand or other gritty material to form said surface sufficiently contracts the compartment at 75 top to insure ignition. The tapering form of compartments may, however, be employed with advantage when these are made of metal and the friction-surface by means of cutting, 80 corrugating, or otherwise mechanically roughening the friction-surface thereof.

We are aware that match-holders constructed so that the withdrawal of a match therefrom will cause its ignition, and that isolating 85 match-heads from each other are not new in a broad sense, and we do not desire to claim such features, broadly.

Having now described our invention, what we desire to claim and secure by Letters Patent 90 is—

1. In a match-safe, a holder or receptacle for the matches, composed of a series of corrugated or fluted sections closed and hinged together at one end, as at C, and provided 95 with a friction-surface at the open end, and an inclosing case or stand, A, for the same, all combined, constructed, and operating substantially as and for the purpose specified.

2. In a match-safe, a holder or receptacle 100 for the matches, composed of a series of corrugated or fluted sections, intervening flat sections or leaves provided with a friction-surface at one end and hinged together and to the fluted sections at the opposite closed end, 105 and a lid hinged to one of the outer leaves, constructed and operating substantially as described, for the purpose specified.

3. In a match-safe, the combination of an inclosing-case with a holder or receptacle for 110 the matches, composed of a series of corrugated or fluted sections, intervening flat sections provided with a friction-surface at one end and hinged together and to the fluted sections at the opposite end, and a lid hinged to one of 115 the outer leaves, substantially as and for the purposes specified.

4. In a match-safe, a holder or receptacle, B, for the matches, composed of a series of corrugated or fluted sections provided with a 120 friction-surface, as set forth, the open-sided holder B', having hinged lid b^2 and pin P, and the inclosing-case A, having slot S, all combined, constructed, and operating as and for the purposes specified. 125

In testimony whereof we affix our signatures in presence of two witnesses.

JULIUS RIEDEL.
ALBERT PFLÜGER.
